UNITED STATES PATENT OFFICE.

KARL H. GETTNER, OF DETROIT, MICHIGAN.

SASH-REGULATING DEVICE.

Application filed November 19, 1923. Serial No. 675,708.

This invention relates to a sash regulating device, and has special reference to that class of devices used in the body, walls and doors of vehicles, particularly automobiles for adjusting sash relative to said walls and doors. My invention aims to provide a sash regulating device that may be bodily mounted in the framework of a door or wall of an automobile body for safely raising and lowering a sash, pane of glass, or rigid transparent member relative to a sash opening, the sash being guided to and from a sash well or pocket in which the device is located and operable from the inner side of the door wall.

My invention further aims to provide a sash regulating device embodying an endless drum actuated flexible member attached to a sash for raising and lowering the sash, and associated with the drum is a counterbalance which facilitates raising the sash, the counterbalance being stressed or placed in active condition when the sash is lowered. The weight of the sash assists in placing the counterbalance in an active position and novel means is employed for holding the sash in adjusted position.

My invention further aims to furnish a sash regulating device with a novel locking device adapted for holding a sash in adjusted position, the locking device being automatically released when the sash regulating device is actuated to raise or lower the sash, otherwise the locking mechanism preventing vibrations of an automobile from causing the sash to be lowered when in a raised position.

My invention still further aims to accomplish the above results by a compact and durable structure that will be hereinafter specifically described and then claimed, and reference will now be had to the drawings, wherein.

Figure 1 is a view of the inner side of a door, partly broken away and partly in section, showing my sash regulating device therein with the sash in a midway position;

Fig. 2 is a vertical sectional view of the same taken on the line II—II of Fig. 1;

Fig. 3 is a horizontal sectional view taken on the line III—III of Fig. 1;

Fig. 4 is a longitudinal sectional view of the winding drum and counterbalance;

Fig. 5 is a cross sectional view of the drum shown in Fig. 4;

Fig. 6 is an enlarged horizontal sectional view taken on the line VI—VI of Fig. 2;

Fig. 7 is a detail view of a spring pressed cam latch forming part of the device;

Fig. 8 is a vertical sectional view of a portion of another form of sash regulating device;

Fig. 9 is a front elevation of part of the device shown in Fig. 8;

Fig. 10 is a longitudinal sectional view of the locking mechanism for the device shown in Figs. 8 and 9, and

Fig. 11 is an enlarged cross sectional view taken on the line XI—XI of Fig. 10.

As set forth in the beginning, the sash regulating device may be mounted in a hollow wall for raising a sash to and from an opening in the wall, and as showing the adaptation of my invention to a door, that may form part of an automobile body, the reference numeral 1 denotes a door frame 70 having a sash opening 2 and a sash well or pocket 3. Between the opening 2 and the well 3 is a sill 4 having a sash opening 5 and movable through said opening is a sash 6 having its side edges slidable in channel 80 guides 7 mounted in the side walls or rails of the door frame. The sash in this instance is in the form of a glass plate and its lower edge is supported in a channel member 8 having a central depending arm 9 provided 75 with a head 10. The head 10 is made of two separable parts affording side grooves 11, as best shown in Fig. 6 and extending into these grooves are the edges 12 of an oblong vertically disposed casing or supporting member 13 mounted in the well 3 and attached to the sill 4 and the bottom wall of the well by screws 14 or other fastening means. The edges 12 of the casing 13 are formed by a slot 15 approximately the full 85 length of the casing 13 so that the head 10 may ride in the slot from one end of the casing to the opposite end. The casing will therefore cooperate with the channel guides 7 in guiding movement of the sash 3 in the door frame.

The casing or supporting member 13 has a detachable wall 16 and mounted in said wall, adjacent the upper end thereof is a bushing 17 for a rotatable drum shaft or arbor 18 which has its inner end squared or provided with facets so that the end wall 19 of a drum 20 may be fixed to said arbor by a nut 21 or other fastening means. The drum 20

is in the form of a spool or sheave to which are attached, as at 22 the ends of the cables or flexible members 23 and 24 which are reversely wound upon the drum so that when one cable is wound thereon the other cable will be unwound. The cable 23 is trained over a sheave or pulley 25 depending from the upper wall of the casing 13 and the cable 24 is trained under the sheave or pulley 26 mounted on the bottom wall of the casing 13, said cables being connected at the head 10 and attached thereto by any suitable fastening means, designated 27.

On the arbor 18 against the detachable wall 16 is a toothed wheel 28 normally engaged by a spring pressed pawl 29 pivotally mounted on the detachable wall 16, said pawl having a right angularly disposed cam 30 projecting over the end of the arbor 18. Slidable on the inner end of the arbor 18 is the socket portion 31 of a crank or handle 32, said socket portion having a substantially V-shaped slot 35 into which extends a pin 34 of the arbor. The inner end of the socket portion 31 has a peripheral flange 35 adapted to engage the cam 30 of the pawl or latch 29 and raise said pawl out of engagement with the toothed wheel 28.

By swinging the crank or handle 32 in either direction, the crank or handle 32 moves inwardly, towards the wall 16, causing the peripheral flange 35 to elevate the pawl 30. This inward movement of the crank or handle 32 is accomplished by virtue of the pin and slot connection between said handle and the arbor, and by rotating the crank or handle 32 the sash may be raised or lowered.

In the drum 20 is a counterbalance in the form of a spiral band spring 36 which has its inner convolution attached to the stationary bushing 17, as at 37, and its outer convolution attached to the peripheral wall of the drum 20, as at 38. The expansive force of the spring is adapted to assist in raising the sash 6 and when the sash is lowered the spring is wound and placed under additional tension.

The inner panel or facing 39 of the door frame has an opening 40 providing clearance for the arbor 18 and the spring pressed pawl or latch 29.

Reference will now be had to Figs. 8 to 11 showing what may be considered a simple form of my sash regulating device. Instead of using the casing 13 a single supporting member 41 may be employed corresponding somewhat to the wall 16 of the casing 13. The sash 6 may be solely guided in the guides 7 and the sheaves 25 and 26 may be supported on angular extensions 42 of the supporting member 41, which has its lower end fixed to the bottom rail of the door frame 1 and its upper end fixed to the sill 4.

The supporting member 41 adjacent its upper end, has an opening 43 and mounted on said supporting member, at the opening 43, is a race member 44 and a lock housing 45 which also contains a race. The drum 20 has a hub portion 46 engaging anti-frictional bearings 47 in the race member 44, and the hub portion 46 is suitably fixed on the shank 48 of an arbor 49 mounted in an inner race member 50 supported by anti-frictional bearings in the lock housing 45. The arbor 49 has a transverse opening 51 and slidable in said opening is a plunger 52 having teeth 53 to engage teeth 54 formed on the inner wall of the lock housing 45, as best shown in Fig. 11. The inner end of the plunger 52 has a stem 55 surrounded by a coiled expansion spring 56 pressing against the plunger 52 to hold it normally in a locked position relative to the housing 45, yet permitting of said plunger being retracted so that the arbor 49 may be turned in either direction in the housing 45. Attached to the stem 55 and embracing a portion of the arbor 49 is a yoke 57 arranged in a semi-circular recess 58 of a sleeve or socket portion 59 forming part of the crank or handle 60. The socket portion 59 is slotted, as at 61, to provide clearance for the plunger 52 and remaining cam portions 62 of the handle socket 59 are adapted to engage the ends of the yoke 57 and shift said yoke when the handle or crank 60 is turned in either direction.

The outer end of the arbor 49 has a transverse pin 63 extending into a slot 64 of the handle socket 59 to retain the handle socket normally on the arbor and about the handle socket 59 is a sleeve 65 that may be shrunk or otherwise fixed on the handle socket, said sleeve being cut away, as at 66, to provide clearance for the plunger 52.

An apertured escutcheon plate or cover 67 may be mounted on the panel 39 to inclose the outer end of the housing 45.

In this simple form of my invention movement of the handle or crank 60 in either direction causes the plunger 52 to be retracted and the arbor 49 can be rotated in either direction to raise or lower the sash 6.

It is believed that the operation and utility of my sash regulating device will be apparent without further description, and while in the drawings there are illustrated the preferred embodiments of my invention, I would have it understood that the structural elements are susceptible to such changes as fall within the scope of the appended claim.

What I claim is:—

In a sash regulating device wherein a sash is adapted to be raised and lowered in a sash well formed by a frame having a sill, a supporting member mounted in the sash well with its lower end attached to the frame and

its upper end attached to the sill, angular extensions on said supporting member, sheaves carried by the angular extensions of said supporting member and removable with said supporting member, a flexible member trained over said sheaves and adapted for raising and lowering the sash relative to said sill, a winding arbor supported from said supporting member, a drum on said arbor

and to which drum the flexible member is attached and wound thereon, said sheaves having the axes thereof in a plane at a right angle to the axis of said winding arbor and drum, and means supported from said supporting member adapted to prevent free rotation of said winding arbor.

In testimony whereof I affix my signature.

KARL H. GETTNER.
